UNITED STATES PATENT OFFICE.

SYLVANUS E. MILLER, OF JERSEY CITY, NEW JERSEY, ASSIGNOR TO
WILLIAM BELL, OF NEW YORK, N. Y.

MEANS FOR LIGHTING LAMPS.

SPECIFICATION forming part of Letters Patent No. 312,285, dated February 17, 1885.

Application filed February 6, 1884. (No model.)

To all whom it may concern:

Be it known that I, SYLVANUS E. MILLER, of Jersey City, in the county of Hudson and State of New Jersey, have invented a certain 5 new and useful Improvement in Means for Lighting Lamps, of which the following is a specification.

The object of this invention is principally to provide a simple and convenient means for 10 lighting street-lamps. I will describe means embodying my invention, and then point out its various features in claims.

In the accompanying drawings, Figure 1 is a longitudinal section of a lamp-lighting apparatus embodying my improvement. Fig. 15 2 is a side view of a portion of the same. Fig. 3 is a top view thereof. Fig. 4 is a transverse section thereof, taken on the plane of the dotted line $x-x$, Fig. 1. Fig. 5 is a side view of 20 a lamp-post and lamp. Fig. 6 is an enlarged sectional elevation of the lamp-burner and its appurtenances. Fig. 7 is a sectional elevation of a lamp-lighting apparatus of modified form embodying my improvement. Fig. 8 is a sec- 25 tional end view of a part of the same. Fig. 9 is a top view of another part of the same. Fig. 10 is a side view of a lamp-post and lamp. Fig. 11 is a vertical section, on a larger scale, 30 of part of the lamp-post. Fig. 12 is a vertical section of the same part of the lamp-post, but taken in a plane at right angles to Fig. 11; and Fig. 13 is a horizontal section of the same part.

Similar letters of reference designate corresponding parts in all the figures.

I will refer first to Figs. 1, 2, 3, 4, 5, and 6.

A designates a battery, which may be of any suitable form.

B designates an induction-coil. The poles 40 of the battery are connected by wires a to the ends of the primary wire of the induction-coil. The battery A, as here shown, is inclosed in a case, C, and the induction-coil B in a case, D. The cases C and D may be made of any suitable material. Each case has a removable 45 cover provided with a screw-threaded rim or flange, whereby it may be securely fastened in place. A tube, E, connects the cases C D together. This tube may be made of metal 50 or other suitable material. As here shown, it is screwed into the removable cover of the

case C and into the bottom of the case D. The tube E has a longitudinal slot, b , terminating at the upper end in a lateral extension, b' . A rod, c , extending from one of the plates of the 55 battery A—as, for instance, from its zinc plate—has at the upper end a lateral projection, c' , that passes through the slot b of the tube E. By taking hold of the projection c' the plate may be lifted, and by slipping this 60 projection c' into the lateral extension b' of the slot b the plate may be suspended above the liquid of the battery while the battery is out of use. The wires a extend through the tube E.

From the cover of the case D, containing the induction-coil, a metal tube, F, extends. This tube will be of a convenient length for reaching any lamp to be lighted. At the upper end it has secured to it a metal arm, F', which bends or curves downward toward one end and upward toward the other end. A wire, d , extending from one end of the secondary wire of the induction-coil, is connected to a binding-screw, e , extending from the tube F. 75 A wire, d' , extending from the other end of the secondary wire of the induction-coil, extends through the tube F to the upper part, thence through it to a piece of metal, f , which is arranged at one end of the arm F', but insulated therefrom by a piece of insulating material, g . As here shown, the piece of insulating material g is screwed into the end of the arm F', and the piece of metal f is screwed into the piece of insulating material g . The 80 wires a d d' are intended to be covered with insulating material.

The burner of the lamp-post shown is intended to be used for gas. It is therefore provided with a cock, h , whereby the gas may 90 be turned on and off. This cock has an L-shaped arm, h' , affixed to it. The arm F' may be engaged with the L-shaped arm h' , for the purpose of operating the gas-cock h . The arm h' , the cock h , the gas-pipe, and the burner 95 are made of metal; hence when the arm F' is placed in contact with the arm h' a path of conducting material is afforded from the arm F' to the burner. The burner is provided with a point, i , of platina or like metal. Another point, i' , of the same metal, is also provided. This point i' is arranged close to the 100

point *i*, so that a spark of electricity passing between them will ignite gas escaping from the burner. The point *i'* is connected to a wire, *j*, which at the lower end is connected 5 to a metal button, *k*. When the arm *F'* is forced against the arm *h'* of the gas-cock, so as to turn on the gas, the metal piece *f* will make contact with the button *k*, and there-
upon a spark or sparks will pass between the 10 points *i i'*, and the gas escaping from the burner will be ignited.

The construction shown in Figs. 8, 9, 10, 15 11, 12, and 13 is very similar to those which have been already described. The battery and induction are similarly connected, but are arranged in a single case, which may be carried in a satchel. The rod *c* of the zinc plate of the battery may be raised and fastened in any desirable position by a set-screw, *c'*.

20 The gas-cock *h* of the lamp-post (shown in Figs. 10, 11, 12, and 13) is arranged very low down, where it can easily be reached. It is operated by a key, *F'*. This key is T-shaped, and the end which is adapted to engage with 25 the gas-cock has a central recess, *l*, and notches *l'* across the end. The central recess, *l*, fits the stem of the gas-cock, and the notches *l'* engage with ribs projecting from the stem of the cock. The key *F'* is made of metal. The wire *d*, ex- 30 tending from the secondary wire of the induction-coil, is connected to a binding-screw secured to the key, so as to be in electrical communication with the key. The wire *d'*, extending from the secondary wire of the induction-coil, is connected to a binding-screw secured to a plug of insulating material, *m*, which is inserted in the key. The wires *d d'* are covered with insulating material, and are sufficiently long to enable the key to be moved 35 conveniently. A wire, *d''*, extends from the plug *m* to a projection, *n*, from an arm, *o*, that extends from the key. The projection *n* consists, as here shown, of a screw fitted into a block, *p*, of insulating material that is inserted 40 in the arm *o*. When the key is applied to the stem of the gas-cock, electrical communication is established between the wire *d* and the burner, and when the key is turned the projection *n* makes contact with the button *k*, and 45

communication is thereby established between 50 the wire *d'* and a point like the point *i'*, here-
tofore described arranged adjacent to the burner. In this example of my improvement it is of course desirable that the stem of the gas-cock and key shall be so peculiarly shaped 55 that no ordinary key or wrench can be used to operate the cock.

What I claim as my invention, and desire to secure by Letters Patent, is—

1. In a portable lamp - lighting apparatus, 60 the combination of a source of electricity, an induction-coil connected therewith, and an electric conductor or conductors having terminals insulated from each other, said apparatus being adapted for use in conjunction with a lamp 65 having electrical conductors extending to the burner in such manner that a current of electricity may be conducted from the induction-coil to the burner, substantially as specified.

2. In a portable lamp - lighting apparatus, 70 the combination of a source of electricity, and an electrical conductor or conductors having terminals insulated from each other, said apparatus being adapted for use in conjunction with a device for turning on gas to a lamp, 75 said device having an electrical conductor or conductors extending to the burner, whereby when the gas is turned on a current of electricity will be conducted to the lamp, substantially as specified.

3. In a portable lamp - lighting apparatus, the combination of a battery and induction-coil arranged in separate cases connected by an intermediate tube, a tube or rod extending from the upper case, a device suitable for turning on the gas at the burner, an electrical conductor connecting said device with the induction-coil, and another electrical conductor extending from the induction-coil, and having a terminal insulated from the device for operating the gas-cock, all being so arranged that gas may be turned on and a current of electricity transmitted to ignite gas escaping 85 from the burner, substantially as specified.

S. E. MILLER.
